[57] CLAIM

The ornamental design for a hot/cold therapy sports pack, as shown and described.

DESCRIPTION

FIG. 1 is a perspective view of a hot/cold therapy sports pack, showing my new design;

FIG. 2 is a top plan view thereof;

FIG. 3 is a front view thereof, the rear view being identical;

FIG. 4 is a side view thereof, the other side being identical;

FIG. 5 is a perspective view of a second embodiment of a hot/cold therapy sports pack, showing my new design;

FIG. 6 is a top plan view thereof;

FIG. 7 is a front view thereof, the rear view being identical;

FIG. 8 is a side view thereof, the other side being identical;

FIG. 9 is a perspective view of a third embodiment of a hot/cold therapy sports pack showing my new design;

FIG. 10 is a top plan view thereof;

FIG. 11 is a front view thereof, the rear view being identical;

FIG. 12 is a side view thereof, the other side view being identical;

FIG. 13 is a perspective view a fourth embodiment of a hot/cold therapy sports pack, showing my new design;

FIG. 14 is a top plan view thereof;

FIG. 15 is a front view thereof, the rear view being identical;

FIG. 16 is a side view thereof, the other side view being identical;

FIG. 17 is a perspective view of a fifth embodiment of a hot/cold therapy sports pack, showing my new design;

FIG. 18 is a top plan view thereof;

FIG. 19 is a front view thereof, the rear view being identical; and,

FIG. 20 is a side view thereof, the other side view being identical.

The broken line in the Figures indicates stitching.
